[57] CLAIM

The ornamental design for an automobile actuated wall
proximity indicator, as shown and described.

DESCRIPTION

FIG. 1 is a front perspective view of an automobile
actuated wall proximity indicator showing my new
design;

FIG. 2 is a rear perspective view thereof; and

FIG. 3 is a fragmentary front perspective view thereof
on an enlarged scale, the indicator being fragmentarily
shown for convenience of illustration and two of the
wings of the bracket being bent to show an alternate
position of attachment. The wall studs are shown in
broken lines for illustrative purposes only.
